UNITED STATES PATENT OFFICE.

EDGAR W. BREISCH, OF EDGEWOOD PARK, PENNSYLVANIA, ASSIGNOR TO WESTINGHOUSE ELECTRIC & MANUFACTURING COMPANY, A CORPORATION OF PENNSYLVANIA.

MERCURY-ARC-RECTIFIER STARTING DEVICE.

Application filed December 7, 1921. Serial No. 520,616.

My invention relates to vapor electric apparatus and particularly to means for initially starting such apparatus.

In mercury converters heretofore employed, 5 a rather elaborate starting arrangement has been utilized, and even with this provision, difficulty has sometimes been encountered in securing the automatic starting of the converter after a temporary failure of the supply voltage when the back electromotive 10 force of the direct-current load is relatively high, leaving a considerably reduced effective voltage between the anode and cathode.

An object of my invention is, therefore, 15 to provide a cheap and efficient automatic starting system for vapor converters, such, for example, as mercury arc converters, which admits of operation on low effective voltages.

20 Other objects of my invention, as well as details of construction, whereby my invention may be practiced, will appear more fully in the following description of the nature, mode of operation and the applications of 25 my invention.

According to my invention, I provide, in 30 a well-known type of converter, an auxiliary starting electrode, which is normally immersed in the main cathode and which is 35 adapted to be rendered electrically active upon a slight tilting of the converter, thereby resulting in the formation of an arc between the starting electrode and the anode. The arc thus formed is readily transferred 40 to the main cathode upon the rectifier being returned to its initial position.

The single figure of the drawing is a dia- 45 grammatic view of circuits and apparatus embodying my invention.

In the drawing, a mercury-arc converter 50 1 is shown as comprising an enclosing envelope 2 having main anodes 3 and 4 and a main cathode 5, preferably of mercury, contained therein. The converter 1 is pivotally mounted upon a bearing member 6 which may be supported in any approved 55 manner. An auxiliary filamentary starting cathode 7 is connected by conductors 8 and 9 to circuit terminals 10 and 11, respectively, 60 the several elements being so disposed as to be normally immersed in the liquid.

Upon a slight tilting of the tube, however, 65 sufficient to cause the mercury to assume the position indicated by the dotted line, the auxiliary cathode 7, conductor 9 and circuit

terminal 11 are uncovered, thereby permitting the excitation of the main cathode 5, as hereinafter described. The anodes 3 and 4 are connected, respectively, by conductors 12 and 13 to opposite terminals of a secondary winding 14 of a transformer 15, the primary winding 16 of which is connected by conductors 17 and 18 to a source of alternating-current energy (not shown). A conductor 19 extends from the terminal 10, 60 which is connected to the main cathode 5, to an intermediate tap point 21 on the transformer winding 14. A direct-current load 22 and an actuating winding 23 of a tilting magnet 24 are serially included in circuit 65 70 with the conductor 19.

A tilting lever 25, which is rigidly secured to the converter envelope 2, has one end thereof pivotally connected, by means of a link 26, to a movable core member 27 of the 75 tilting magnet 24. The lower end of said core member carries a switch member 28 which coacts with stationary contact members 29 and 31 to effect the energization of the hot cathode 7 when the converter is 80 tilted sufficiently to uncover the hot cathode 7, the conductor 9 and the circuit terminal 11, as indicated by the dotted line in the drawing. An exciting circuit for the cathode 7 extends from the circuit terminal 11 85 through stationary and movable contact members 29, 31 and 28, respectively, of the tilting magnet 24 and a portion 32 of the secondary winding 14 of the transformer 15 to the main cathode circuit terminal 10. 90

The converter is normally held in tilted position by means of a weight 33 mounted on the lever 25. When the primary winding 16 is energized, as by the closing of a switch 34, which is serially included in the conductor 18, the filament 7 is heated, thereby causing the establishment of an arc between the filament 7 and the anodes 3 or 4. The solenoid 24 is thereupon energized to tilt the converter to an upright position, thus causing the filament 7 to be immersed and hence the transfer of the arc to the main cathode 5. Under favorable conditions, the arc may immediately shift to the mercury cathode 5 as soon as the filament 7 is energized and before 105 the converter has had time to tilt to an upright position.

I have thus provided for the automatic starting of a mercury-arc converter upon the energization of the alternating-current 110

supply line. An additional advantage of immersing the filament 7 in the mercury cathode 5 during normal operation resides in the fact that the filament 7 is protected from the 5 disintegrating effects of the mercury vapor arc-stream.

While I have shown only one embodiment of my invention, for the purpose of describing the nature, the mode of operation and 10 the applications thereof, it is capable of various changes and modifications without departing from the spirit of my invention and I desire, therefore, that only such limitations shall be imposed thereon, as are specifically set forth in the appended claims.

I claim as my invention:

1. In an evacuated electric apparatus, a container, a pair of electrodes forming a space-current path contained therein, one of 20 said pair of electrodes being of a liquid vaporizable material an electron-emitting element immersed in said vaporizable electrode, and means for, at times, exposing said electron-emitting element.
2. In an evacuated electric apparatus, the combination with a container, of an anode and a liquid cathode disposed therein, and an auxiliary cathode having an electron-emitting portion immersed in said liquid 30 cathode and means for tilting said container, said electron-emitting portion being exposed upon tilting of said container.

3. In an evacuated electric device, the combination with an enclosing envelope, of an 35 anode and a liquid cathode disposed therein, a tiltable mounting for said envelope, an auxiliary solid cathode having an electron-emitting portion normally immersed in said liquid, said electron-emitting portion being 40 exposed when said envelope is in its tilted position, and means for exciting said auxiliary cathode.

4. In an evacuated electric apparatus, the combination with a container, of an anode 45 and a liquid cathode forming a space-current path therein, a tiltable mounting for said container, an auxiliary solid electrode having an electron-emitting portion normally immersed in said liquid cathode, said electron-emitting portion being exposed to serve 50 as a starting cathode upon the tilting of said container, means for energizing said auxiliary cathode, and means for deenergizing said auxiliary cathode and for causing said container to return to its normal operating posi-

tion after the initiation of a current between one of said cathodes and said anode.

5. In an evacuated electric apparatus, the combination with a container, of an anode and a liquid cathode forming a space-current 60 path therein, an auxiliary starting cathode having an electron-emitting portion, said portion being so disposed as to be normally immersed in said liquid electrode, means for exposing said electron-emitting portion, 65 means for energizing the same as a cathode, and means responsive to the passage of space-discharge currents through said apparatus for immersing and deenergizing said electron-emitting portion. 70

6. The combination with a mercury-vapor rectifier, of a heating member normally immersed under the active surface of the mercury, means for, at times, exposing said heating member over the active surface of the 75 mercury and means for energizing said heating member.

7. The combination with a mercury-vapor space current device, of an auxiliary filamentary cathode immersed in the mercury 80 and means, responsive to the operating conditions of said rectifier, for exposing said filamentary cathode from the mercury.

8. The combination with a mercury-vapor rectifier, of an auxiliary filamentary cathode 85 normally immersed in the mercury during the normal operation of the rectifier, means for biasing the rectifier to a tilted position, said filamentary cathode being so disposed as to be exposed upon the tilting of said 90 rectifier, means for energizing said filamentary cathode and means responsive to the establishment of an arc for tilting the rectifier to normal operating position.

9. In a space-current device, an anode, a 95 solid electron-emitting electrode, a liquid, and means for causing said liquid to cover and expose said electrode.

10. A space current device comprising a liquid electrode, an auxiliary electrode having an electron emitting portion, means responsive to the current through said device for exposing said electron emitting portion 100 and for immersing it in said liquid, and for energizing and deenergizing said electron 105 emitting portion.

In testimony whereof, I have hereunto subscribed my name this 25th day of November, 1921.

EDGAR W. BREISCH.
